UNITED STATES PATENT OFFICE.

FRANK AMATO, OF NEW YORK, N. Y.

DOOR-LOCK.

1,240,403.

Specification of Letters Patent. Patented Sept. 18, 1917.

Application filed March 1, 1916. Serial No. 81,302.

To all whom it may concern:

Be it known that I, FRANK AMATO, a subject of the King of Italy, who have declared my intention of becoming a citizen of the 5 United States, residing at the city of New York, borough of Manhattan, county and State of New York, have invented a certain new and useful Door-Lock, of which the following is a specification.

10 This invention is a door lock for general use, and among the objects sought to be attained are, first, to afford security by the employment of certain bolts adapted for engagement with keepers positioned at the 15 top rail and at the floor sill in addition to the ordinary keeper on the side of the door jamb; second, to so combine a spindle-controlled means with a key-operated means that said spindle or the key-operated means 20 may be used independently of each other or conjointly with each other; third, that the lock bolt may be operated independently of the top bolt and the bottom bolt; and, fourth, 25 that the lock bolt may be retained in the projected or shut position independently of the operation either of the spindle-controlled means or the key-operated means.

The invention, in one aspect thereof, embodies a bolt slidable within a suitable casing, and a spindle coöperating with said bolt for imparting the sliding movement thereto, combined with one or more other bolts positioned at the top or bottom (or both) of the door, rods connected with said 35 top and bottom bolts and extending inwardly of the lock casing, and an operating gear carried by the knob spindle and positioned for engagement with racks provided on the lock bolt and on the connecting rods, where- 40 by the rotation of said gear operates to impart movement simultaneously to the lock bolt and to the additional bolts in order to project said bolts or to retract the same according to the direction of rotation of the 45 spindle and said gear.

Coöperating with the lock bolt are a plurality of separate dogs each adapted to retain said bolt in a projected position, thus precluding the spindle and the gear from 50 actuating the bolt or bolts. It is preferred to employ two of said dogs, one of which is controllable by key-actuated means,

whereas the other is operated by an independent member operable at will from the inside of the door.

55

The key-actuated means is in effect a cylinder lock equipped with a polygonal stud positioned for interlocking connection with an actuator which coöperates directly with one of said dogs. Said actuator is 60 mounted for rotative movement within the lock-casing and is positioned for contact with said dog in a manner to retain the dog either in contact with a shoulder of the lock bolt or to retract the dog from the path of 65 the shoulder in order to free the lock bolt from the restraint of the dog.

The other dog referred to (dog J) is under the control of a separate rotatable actuator provided with a hand-operated 70 member accessible from the inside of the door so as to be shifted at will, thus locking the bolt against movement independently of the knob spindle or the key-actuated means.

Provision is made for the operation of 75 the lock bolt independently of the top bolt and bottom bolt. The gear is mounted for sliding movement on an angular part of the knob spindle, and coöperating with said gear is a spring and a shifter which position 80 the gear so that it meshes with all the racks in order to operate the lock bolt, the top bolt and the bottom bolt simultaneously. The shifter is free to be operated by hand 85 in order to slide the gear along the knob spindle against the tension of the spring, whereby the gear is free from mesh with the racks on the rods associated with the top and bottom bolts but said gear remains in mesh with the rack on the lock bolt, thus 90 operating the lock bolt without operating the top and bottom bolts. But by adjustment of the shifter, the spring retains the gear into mesh with the racks of all the bolts, so as to operate the latter simulta- 95 neously when desired.

Other features and advantages of the invention will appear from the following detailed description taken in connection with the drawings, wherein—

100

Figure 1 is a side elevation of a multiple bolt lock embodying this invention, the bolts being shown in their retracted positions.

Fig. 2 is an enlarged view, partly broken

away, and in section, illustrating the bolts in their projected positions by dotted lines.

Fig. 3 is a vertical section on the line 3—3 of Fig. 2.

5 Fig. 4 is a horizontal section on the line 4—4 of Fig. 2.

Fig. 5 is an enlarged detail view of one of the locking dogs associated directly with the double or U-bolt.

10 Fig. 6 is a cross section through the manually-operated element adapted to control one of the locking dogs associated with the double bolt.

A designates a lock casing constructed, as 15 usual, of two separable parts adapted to be fastened together and to a door by the screws a. The casing is provided on one side with openings b adapted to accommodate the members of a double or U-shaped

20 bolt B, and in addition to the openings b said casing A is provided with chambered extensions b' b'', the chambers of said extensions accommodating the two rotatable members for controlling the locking dogs, 25 as will be hereinafter more fully described.

The casing is provided, furthermore, with suitable openings in front and rear thereof, which openings are in line with each other and are positioned in a plane intermediate 30 the two members of the U-bolt B, whereby provision is made for the accommodation of a knob spindle C, the latter passing through the casing and the door so as to be rotatable freely therein, and said spindle being poly- 35

gonal or square in cross section for the reception of a correspondingly shaped boss or hub d of an operating gear D. This operating gear is capable of a limited sliding movement upon the square part of the knob 40 spindle so that in all positions of the gear it will turn or rotate with said spindle, but the gear is normally pressed toward one side of the lock casing by means of a coiled spring d', the latter being fitted loosely upon 45 the spindle and engaging with the gear so as to retain it in a predetermined operative relation to the plurality of bolts.

One member of the double bolt B is provided on its inner edge with a series of teeth 50 e constituting a rack, with which rack the teeth of the operating gear D is normally in mesh, as a result of which the gear is adapted to be rotated in one direction by the spindle so that the double bolt B is projected 55

into a locking position so as to engage with a keeper on the door jamb, but when the spindle and the gear are rotated in an opposite direction the gear actuates the rack e for the purpose of retracting the 60 bolt within the lock casing. The gear is free from engagement with one member of the double bolt, but has meshing engagement with the other member of said bolt, and in addition to operating the double 65

bolt B, said gear is adapted to actuate other

sliding members F, G, which members in turn impart movement to other bolts F', G', as shown more particularly in Fig. 1. Said bolts F', G' are positioned at the top and bottom, respectively, of the door to which the lock is applied, and, as shown, said bolts are slideable in suitable guides f and are adapted for engagement with suitable keepers g attached to the top of the door frame and to the sill of the door, respectively, as clearly shown, said sliding bolts being connected by intermediate rods f' with the sliding members F, G. These sliding members F, G operate within suitable guideways provided interiorly of the lock casing, see Fig. 2, and in addition to the guideways said sliding members are provided with slots h with which are engaged screws h' fastened to the lock casing. The sliding members are in the same transverse plane with each other and the plane of the sliding members is to one side of the bolt B, said sliding members being provided on their opposing edges with the teeth i adapted to form racks whereby the two sliding members F, G are positioned for engagement with the teeth of the operating gear D, said gear being sufficient in length to mesh with the rack e of the double bolt and with the racks i of the two sliding members F, G, as a result of 90 which the rotation of the gear by the knob spindle in one direction operates the three bolts B, F, G, so as to move said bolts to their projected positions, whereas the rotation of the operating gear in the opposite direction 100 by the knob spindle draws the bolts simultaneously to their retracted positions. The sliding members F, G are under the control of springs I, each spring being housed within the casing adjacent to one of the sliding members, and the respective ends of the spring being attached to the proper sliding member and to the casing, said springs operating to draw the sliding members inwardly of said lock casing. 110

Within the chambered extensions b', b'' of the lock casing are positioned the dogs J, K, each dog being pivoted by a suitable pin to the lock casing. The dog J is adapted for engagement with a notch j provided in one member of the double bolt B, whereas the other dog K is positioned to fit into a notch k provided in the other member of said bolt, see Figs. 2 and 5. 115

The dog J is controlled by a rotatable chambered member L, the same being positioned within the chambered extension b''. Said chambered member L is provided with a sleeve l, into which is screwed a threaded operating stem L', the same having a head 120 exposed outside of the lock casing, as shown in Figs. 1 and 3, whereby the part L' is adapted to be operated for rotating the member L. This member L is in the form 125 of a casing adapted to receive within itself 130

the pivoted dog J, and when the chambered member is in one position the dog is pressed outwardly through a radial slot in the member L by the action of a suitable spring, so that the dog will engage with the notch *j* for the purpose of locking the bolt in its projected position.

Coöperating with the other dog K is another chambered rotatable member M which is key-actuated instead of being operated by hand directly, as is the case with the dog J. This rotatable member M is positioned within the chambered extension *b'*, and as shown in Fig. 5 said member M is chambered and provided in one side with an opening or throat *m*. The chambered member M is positioned to receive within itself the dog K, the latter being actuated by a spring *m'*, and when the parts are in the position of Fig. 5 the spring *m'* throws the dog outwardly through the throat *m* in order that the free end of the dog will engage with the notch *k* of the double bolt.

The rotatable member M is provided with a sleeve *n* having a square or polygonal opening into which fits the squared part of a spindle *n'* forming an extension of the tumbler barrel N, the latter being associated with the pin bolt mechanism incased within a cylinder lock N'. This cylinder lock is key-controlled, and when the proper key is inserted the pins are retracted in order that the barrel N and the spindle *n'* may be rotated for the purpose of imparting rotative movement to the member M, whereby the key-operated lock may be manipulated and rotated for the purpose of turning the member M so as to either retract the dog K or to allow the dog to be projected into locking engagement with the bolt B.

As heretofore described, the knob spindle and the gear are operated to impart movement simultaneously to the bolt B and the members F, G which control the top and bottom bolts of the door lock, but under some circumstances it may be considered inadvisable to actuate the top and bottom bolts and the slideable members F, G. Accordingly, provision is made for shifting the operating gear D so that the teeth thereof will be free from engagement with the racks *i* of the slideable members F, G, but at this time the operating gear remains in mesh with the rack *e* of the double bolt, whereby the rotation of the knob spindle will actuate the double bolt only, the slideable members F, G and their corresponding bolts being idle. Various means may be employed for imparting this adjustment to the gear D, but in the embodiment shown I employ a shifter O, the same being in the form of a pivoted plate positioned within a suitable recess of the lock casing, so that the plate will have engagement with the gear D. In a preferred form the pivoted shifter O is forked

toward one end in order that it may partly fit around the knob spindle, as shown in dotted lines in Fig. 2. The shifter is positioned for engagement with one side or face of the gear D, whereas the spring *d'* engages with the other face of said gear. The shifter is operated by a device positioned for access on the outside of the lock casing. As shown, this device is a screw P having an exposed operating head *p*, see Fig. 6. The screw is normally retracted from engagement with the shifter O so that the spring *d'* will press the gear D into position for engagement with the racks *e*, *i* of the bolt B and the members F, G, respectively. It is apparent that the screw P may be turned for the purpose of moving the shifter inwardly to the position of Fig. 6, whereupon the shifter moves the gear D along the knob spindle so that the gear is free from engagement with the slideable members F, G, but remains in engagement with the rack *e* of the double bolt B.

It is thought that the operation and advantages of this invention will be apparent from the foregoing description taken in connection with the drawings.

Having thus fully described the invention, what I claim as new and desire to secure by Letters Patent is:

1. In a lock, the combination with a lock bolt, and a knob spindle, of an additional bolt, a gear for operating the lock bolt and the additional bolt simultaneously, a dog coöperating with the lock bolt, and means for shifting the gear in a direction to free it from the additional bolt while retaining said gear in operative relation to the lock bolt.

2. In a lock, the combination with a lock bolt, and a knob spindle, of an additional bolt, a gear slideable on the knob spindle and adapted to impart movement to the lock bolt and the additional bolt simultaneously, means for shifting said gear so as to free it from the additional bolt while retaining it in mesh with the lock bolt whereby the gear imparts movement to the lock bolt to the exclusion of the additional bolt, and a dog coöperating with the lock bolt.

3. In a lock, the combination with a lock bolt, and a knob spindle, of a plurality of additional bolts, a gear on the spindle for operating the lock bolt and said additional bolts simultaneously, means for shifting said gear so as to operate the lock bolt to the exclusion of the additional bolts, and a dog coöperating with the lock bolt, said dog being operable at will to shift it with respect to the lock bolt.

4. In a lock, the combination with a lock bolt, and a knob spindle, of an additional bolt, a gear slidably mounted on the knob spindle, means for retaining said gear in mesh with the lock bolt and the additional

- bolt so as to operate the same simultaneously, and means for positioning said gear out of mesh with the additional bolt while it remains in mesh with the lock bolt so as to operate the latter.
5. In a lock, the combination with a lock bolt, and a knob spindle, of an additional bolt, a gear slidably mounted on the knob spindle, a spring acting on the gear to retain it in mesh with the lock bolt and the additional bolt, and a shifting plate in contact with said gear, said plate being operable at will for moving the gear upon the spindle so as to disengage it from the additional bolt and permit it to operate the lock bolt.
6. In a lock, the combination with a lock bolt, and a knob spindle, of a dog coöperating with said lock bolt, and a rotatable chambered actuator incasing said dog, a spring for projecting the dog, and means for rotating the actuator into contact with the dog to retract it from engagement with said lock bolt.
7. In a lock, the combination with a lock bolt, and a knob spindle, of a dog coöperating with said lock bolt, a rotatable chambered actuator incasing said dog and operating to retract it from engagement with said lock bolt, and key operated means for imparting rotative movement to said actuator.
8. In a lock, the combination with a lock bolt, and a knob spindle, of a spring actuated dog coöperating with said lock bolt, a rotatable chambered actuator incasing said dog and operating to retract it from engagement with said lock bolt, and means operable at will for imparting rotative movement to said actuator.

In testimony whereof I have hereunto subscribed my name.

FRANK AMATO.
